(57) **CLAIM**

The ornamental design for a five lever, five spring centrifugal clutch, as shown.

DESCRIPTION

FIG. 1 is a front perspective view of a five lever, five spring centrifugal clutch showing my new design;

FIG. 2 is a top plan view thereof;

FIG. 3 is a front view thereof; and,

FIG. 4 is a rear view thereof.

I further disclaim and do not include as part of my invention the bottom portion, which is shown with broken lines.
